UNITED STATES PATENT OFFICE.

VERNON H. JOHNS, OF WAUCONDA, ILLINOIS.

TRY-SQUARE.

Specification of Letters Patent.

Patented Dec. 3, 1918.

1,286,332.

Application filed October 27, 1917. Serial No. 198,830.

To all whom it may concern:

Be it known that I, VERNON H. JOHNS, a citizen of the United States, residing at Wauconda, in the county of Lake and State of Illinois, have invented certain new and useful Improvements in Try-Squares, of which the following is a specification.

This invention relates to an improved try-square and the principal object of the invention is to provide an improved attachment 10 for a try-square which attachment will permit the try-square to be used as a miter square.

Another object of the invention is to so 15 construct this attachment that it will not interfere with the try-square being used in the ordinary manner, as a try-square.

Another object of the invention is to so 20 construct this device that a conventional construction of try-square may be used and to further so construct the attachment that it may be put in place upon a try-square already in use.

Another object of the invention is to provide 25 a device of the character described which will be simple in construction and easy to operate.

This invention is illustrated in the accompanying drawings, wherein:—

30 Figure 1 is a view showing a try-square in top plan and provided with the improved attachment.

Fig. 2 is a transverse sectional view taken along the line 2—2 of Fig. 1.

35 Fig. 3 is a transverse sectional view taken along the line 3—3 of Fig. 1, and

Fig. 4 is a view showing the try-square in side elevation, one end portion of the handle section of the try-square being broken 40 away.

This try-square is provided with a blade 10, one arm 10' of which carries the handle plates or strips 11 which plates or strips may be formed either of metal or wood. An 45 arcuate slot 12 is formed in the blade 10 and for use in connection with this slot, there has been provided a scale 13 extending parallel to the slot. A hinged strip or carrier 14 is

secured to the handle portion of the square by fasteners extending into the strips 11 and 50 this hinged strip is provided at one end with the hinge ears 15 positioned above and below the arm 10' of the blade and serving to pivotally mount the miter arms 16 and 17. These 55 miter arms 16 and 17 extend transversely across the blade and are provided with openings 18 and 19 to receive the threaded stem of the fastener 20 which fastener when tightened serves to hold the miter arms in a set 60 position upon the blade.

This square may be used either as an ordinary try-square with the miter attachment in the position shown in Fig. 1 or the miter arms may be moved to a desired point upon the scale as shown and the fastener 65 then tightened, thus holding the miter arms in the set position and permitting this square to be used as a miter square. As this square is of the conventional construction, it will be readily seen that it will not be necessary to provide any special construction of 70 square in order to put the attachment in place and it will be further seen that this attachment may be connected with square already in use, it simply being necessary to 75 provide a slot 12 and then connect the strips 14 with the handle portion of the square.

What is claimed is:—

1. A try-square comprising a blade, handle plates secured to opposite sides of said blade adjacent one end thereof, a hinged strip extending longitudinally along one edge of said blade and having its side edges overlapping and secured to the edges of said handle plates, ears formed on one end of said strip beyond the adjacent ends of said plate, and positioned on opposite sides of said blade, miter arms engaging opposite sides of said blade, and pivotally secured at one end to the inner faces of said ears, and means for simultaneously adjusting and securing said arms in adjusted position, said means also serving as a handle when moving said arms to adjusted position.

2. A square comprising a blade having an 95 arcuate slot, handle plates fitting against

opposite sides of said blade, miter arms engaging opposite sides of the blade and hingedly connected to said plates one of said arms having an opening therein, an extension carried by the opposite arm and movable therewith, said extension being arranged to project through the slot in said blade and through said opening, and a

thumb nut threaded upon the free end of the extension.

In testimony whereof I affix my signature in presence of two witnesses.

VERNON H. JOHNS.
